SHAFT DRILL SAFETY DEVICE

John Branner Newsom, Nevada City, Calif., assignor to Idaho Maryland Mines Corporation, San Francisco, Calif., a corporation of Nevada

Application July 15, 1938, Serial No. 219,422

3 Claims. (Cl. 255—4)

This invention relates in general to a shaft drill such as for example shown in my Patent 2,090,304 of August 17, 1937, and in particular to a safety device applicable thereto.

The shaft core drill as disclosed in my patent above referred to comprises in general a compartment or pilot house for accommodating an electric motor and an operator. Extending downwardly through this pilot house is a shaft 10 operated by said motor and carrying at its lower end a core drill. The pilot house is provided with wall jacks or screws by which it may be secured in any predetermined position within the shaft, not only against the action of gravity but 15 against the torque resulting from the rotation of the core drill against the resistance of the bottom of the shaft. In operating a core drill of this type, it has been found that on several occasions the wall jacks or screws have pulled loose or that 20 the motor was put into operation before the wall jacks were properly tightened. Since the core drill operates against the resistance of the bottom of the shaft, the torque between the drive shaft and the motor was converted into rotary 25 motion of the pilot house. The pilot house continued to rotate until the electric wires leading to the motor were broken, and as a consequence of the rotary motion of the pilot house, the operator was thrown against its inner wall. Fortunately in these instances, and contrary to all rules of probability, the operator within the pilot house 30 was not seriously injured.

In general, the object of this invention is the provision of a switch in the power input to the 35 motor operating the drive shaft, and which is arranged to open automatically upon any relative movement between the pilot house and the shaft or bore in which it is disposed.

The invention possesses other advantageous 40 features, some of which with the foregoing will be set forth at length in the following description where that form of the invention which has been selected for illustration in the drawing accompanying and forming a part of the present specification is outlined in full. In said drawing, one 45 form of the invention is shown, but it is to be understood that it is not limited to such form, since the invention as set forth in the claims may be embodied in a plurality of forms.

Referring to the drawing:

Figure 1 is a vertical mid-section taken through a core drill disposed in a mine shaft or bore and embodying the objects of my invention.

Figure 2 is a section taken on the line 2—2 of 55 Figure 1.

Figure 3 is a diagrammatic illustration of the limit switch and electric circuit used in carrying out the objects of my invention.

As generally shown in Figures 1 and 2 and more specifically shown and described in my aforesaid patent, my invention is embodied in a shaft drill comprising a pilot house 1 provided with suitable wall jacks or screws 2 for securing it in any predetermined position within the mine shaft or bore 3. Extending through the pilot 10 house 1 is a drive shaft 4 carrying at its lower end the core drill 5. Disposed within the pilot house 1 is an electric motor 6 arranged by suitable gearing to rotate the drive shaft 4 and connected by leads 7 and 8 to a source of electric 15 power not shown. Inserted in the lead 7 of the input to the motor 6 is a limit switch 9 secured to the pilot house 1. The limit switch 9 comprises a fixed contact 12 and a movable contact 11 secured to one end of a lever 13. The lever 13 is 20 pivoted intermediate its ends to the switch housing and is provided with a spring 14 which serves normally to hold the contacts 11 and 12 out of engagement. The free end of the lever 13 extends through the switch housing and is provided 25 with a recess 15. In its operative position, the contacts 11 and 12 are held in their closed position against the action of the spring 14 by a pin 16, one end of which is accommodated in the recess 15 while the other end extends through an 30 opening 17 formed in the wall of the pilot house 1 and engages the wall of the bore 3. The pin 16 if desired may be secured to the pilot house 1 by a chain 18.

It will be noted from the above description 35 that after the pilot house 1 is secured in any predetermined position within the mine shaft or bore 3 by the wall jacks or screws 2 and the pin 16 is inserted in its operative position as shown in Figure 2, any relative motion between the pilot house and the bore 3 will serve to trip the pin 16 and thereby permit the spring 14 to move the contact 11 out of engagement with the contact 12, to thereby stop the motor. It is to be further noted that since the limit switch is normally held 40 in its open position by the spring 14, the motor 6 in its open position by the spring 14, the motor 6 45 can not be started until the pin 16 is propped between the lever 13 and the bore 3.

I claim:

1. A device for drilling a bore comprising: a 50 motor compartment; means for detachably securing said compartment in any predetermined position within said bore; a drive shaft depending from said compartment and secured at its lower end to a drill; a motor carried by said 55

- compartment for rotating said drive shaft; and means associated with said compartment and responsive to relative movement between said compartment and said bore for causing said motor to become inoperative with respect to said drive shaft.
2. A device for drilling a bore comprising: a motor compartment; means for detachably securing said compartment in any predetermined position within said bore; a drive shaft depending from said compartment and secured at its lower end to a drill; an electric motor carried by said compartment for rotating said drive shaft; a switch carried by said compartment in circuit with the power input to said motor; and means responsive to relative movement between said compartment and said bore for tripping said switch.

3. A device for drilling a bore comprising: a motor compartment; means for detachably securing said compartment in any predetermined position within said bore; a drive shaft depending from said compartment and secured at its lower end to a drill; an electric motor carried by said compartment for rotating said drive shaft; a switch carried by said compartment in circuit with the power input to said motor; a spring for urging said switch to its open position; and means operating against the action of said spring for maintaining said switch in its closed position so long as there is no relative motion between said compartment and said bore and for opening said switch upon relative motion between said compartment and said bore.

JOHN BRANNER NEWSOM.
